CARTON PARTITION FOR ARTIFICIAL SILK COPS

James A. Montgomery and Ralph D. Morton, Kingsport, Tenn., assignors to Eastman Kodak Company, Rochester, N. Y., a corporation of New Jersey

Application February 24, 1955, Serial No. 490,264

1 Claim. (Cl. 229—42)

This invention relates to partitions for cartons especially adapted to receive real or artificial silk cops wound on conical supports or the like.

There are a large variety of these silk cops which may vary considerably in weight. Typical cops may weigh approximately three, four and six pounds. These weights may vary quite widely with different manufacturers but it can readily be seen that when a large number of cops, perhaps 48, are mounted in a single carton, a heavy package results. Under such conditions the cops are difficult to handle without damaging or marring the delicate yarn unless great care is taken in packaging the individual units.

Our invention is particularly directed to providing a partition which may be placed in a box or carton and which may definitely support the conical ends of the cone-shaped members or supports on which the yarn is wound. These partitions are arranged to be properly spaced so that a major part of the weight of the individual units will be distributed over the entire area of the partition and so that the cops themselves may assist in bearing the weight within the container. Another object of our invention is to provide a partition which may be readily made from a single, generally rectangular sheet of relatively strong fiber board or the like so that these partitions may be die cut from pieces of the material and provided with suitable weakened fold lines and supporting apertures for the conically shaped yarn supports. Still another object of our invention is to provide a partition in which the relative spacing of the partitions may be accurately obtained while loading a carton, placing one partition in the carton and loading a layer of cops therein and placing a second partition in a fixed position with regard to the first and continuing until the carton has been completely filled. Still another object of our invention is to provide a partition having a series of panels, certain panels positioning large and small apertures in axial alignment to receive the ends of a cop support and certain other partitions projecting from the apertured panels and into a position to space the panels one from the other as the carton is loaded by placing successive partitions and successive layers of cops in the carton. Another object of our invention is to provide an integral flange of the partition which may assist in bearing any additional outside weight imposed on the carton of cops. Another object is to provide a dividing partition which will engage and be positioned by special part partitions for use at the top and bottom of the cartons only. Other objects will appear from the following specification, the novel features being particularly pointed out in the claim at the end thereof.

Coming now to the drawings wherein like reference characters denote like parts throughout:

Fig. 1 is a top plan view of a partition blanked from a sheet of suitable material;

Fig. 2 is a perspective view of the blank shown in Fig. 1 partially folded to form a partition;

Fig. 3 is a perspective view of a partition completely folded from the blank shown in Fig. 1;

2

Fig. 4 is a blank die cut from suitable material and illustrating a second preferred form of our invention;

Fig. 5 shows a perspective view of the blank shown in Fig. 4, partially folded;

Fig. 6 shows a perspective view of a completely folded blank in accordance with Fig. 4;

Fig. 7 is an enlarged detail section showing a typical cop which may be packed in a carton in which our improved form of die-cut partitions are used; and

10 Fig. 8 is a detail sectional view showing on a relatively small scale a typical carton or box packed with a series of our improved partitions with the cops in place but omitting the individual wrappings around each cop in order to more clearly illustrate the invention.

15 Our improved form of partitions can be die cut into a generally rectangular form, as shown in Figs. 1 and 4, this being particularly desirable because such blanks are economical and because they may be packed flat for storage, shipment and the like. These blanks are provided with fold lines, preferably weakened to fold readily, and slots so that an operator may rapidly bend them into the desired shape. We have found it convenient to fold these partitions as a box or carton is being loaded and as the partitions are placed into the carton so that each successive layer of cops may be supported in a fixed position and much of the weight of the cops will be taken up by the cops themselves, the partitions serving primarily to hold them in place.

Fig. 1 shows a blank 10 which has been die cut to form 30 a series of large apertures 11 and a series of small apertures 12, the large apertures being formed in the panels 13 and 14 and the small apertures being formed in the panels 15 and 16. The blank 10 is provided with three horizontal (with respect to Fig. 1) fold lines 17, 18 and 35 19. There is also a vertical fold line 20 extending transversely of the panel. The fold lines 17, 18 and 19 and a center slot 21 bound panels 22, 23 and 24, 25, there being a transverse slot 26 in panels 22 and 23 and a transverse slot 27 in panels 24 and 25.

40 With such a blank and with the weakened fold lines described above, a partition as indicated broadly at 29 may be formed by folding the sets of small apertures 12 in panels 15 and about the fold line 20 and the slot 21 starting this folding movement as shown in Fig. 2. By 45 continuing this folding movement and by bending the panels 22, 23 and 24, 25 outwardly, two double walled flanges provide extensions running the length of the partition in one direction, as shown in Fig. 3.

In a second form of our invention shown in Fig. 4, 50 there is a blank 30 having a series of panels 31, 32, 33, 34, 35, 36, 37 and 38 separated or defined by fold lines 39, 40, 41, 42, 43, 44 and 45. The two panels 31 and 34 are provided with small apertures 46 and the panels 35 and 38 are provided with large apertures 47. There is a slot 55 48 extending into panels 32 and 33 and a similar slot 49 extending into panels 36 and 37. When this blank is folded back and forth upon the various transverse fold lines, as indicated in Fig. 5, the large apertured panels lie on one side of the center fold about fold line 42 and the small apertures lie on the opposite side so that when the partition 50 is finally completed, as in Fig. 6, the shape is substantially that of the first-described embodiment of our invention shown in Fig. 3.

Fig. 7 shows a typical yarn cop which may be shipped 65 in a carton or box in which our improved form of partitions are used. It will be noted that this cop 51 has been wound upon a core or support 52 which has one large end 53 and one small end 54. Since the size of these conical ends and cops varies quite widely, we have referred in the 70 specification and claim to a partition plate having "large" and "small" apertures to receive the large and small ends of the cops. It will be noted that the size of these aper-

tures will, of course, vary but our invention includes any size in which a large aperture is designed to receive a large end of a cone support and in which a small aperture is adapted to receive a small end of a conical support.

As will be noted from Fig. 8, a box which may be corrugated or other type of cardboard container may be employed, or a box of any other suitable material can be used. This container which we prefer to make of strong corrugated cardboard, for instance, is preferably of a size to just receive a definite number of silk cops and these may be conveniently loaded by placing in the bottom of the box or container a partition B which might be considered half of the blank partitions in Fig. 1 and Fig. 4 since only the partitions utilizing the large size opening are preferably employed for this purpose. Thus there will be a partition with large apertures and with a double walled spacing extension which is slotted extending upwardly from the bottom. A layer of cops with the large ends 53 of the supports are then inserted in the large apertures 11 or 47 and then a second partition which will be a complete partition, as in Figs. 3 or 6, may be employed, the slotted areas of these partitions being moved downwardly over the slotted areas of the lower outstanding partitions at right angles thereto. Thus the small apertures will be placed over the small ends 54 of the conical supports and a second layer of cops are positioned in the container.

After the required number of layers and partitions are loaded, the top partition T like the lower one may be half of the partition shown in Fig. 3 or Fig. 6; that is, the half having the smaller apertures. This will leave a flat top to lie against the flat top member 61 of the container and since the partitions 29 or 50 lie against the side walls 62 of the container and the upper walls 61 lie against the half partition on the top of the carton, the weight of the cops is well distributed over the entire areas of the top and bottom of the container and the partition plates, while strong, nevertheless are primarily designed to hold the cops in axial alignment so that the conical supports 52 resting on the partitions may assist very materially in supporting the weight of all of the cops. However, should any undue weight be imposed onto the top of the carton of cops, as might result for instance if a heavy weight were placed on top of the carton, in stacking or during shipment, then the integral double-walled flanges on the partitions would serve to bear a greater part of this extra load, to resist the tendency for compression of the carton, and to prevent damage which might result from compression of the yarn wound on the cops.

It will be noticed that with our improved form of die-cut inner layers for cartons that we have illustrated forms of our invention which are readily adaptable for use in the rapid loading of boxes or cartons of cops since these partition members may lie flat in storage and may be

readily folded up into the required shape before or after a layer of cops has been placed in the container. Moreover, if desired and some care is used, it is possible to unfold the partitions into their original flat form and reuse them if this can be economically accomplished.

While we have shown two forms of our invention which are well adapted for use, we consider as within the scope of our invention any such forms as may come within the scope of the appended claim.

Having thus described our invention, what we claim is new and desire to secure by Letters Patent of the United States is:

Interengaging partitions for containers used in shipping yarn carried by yarn cop supports having one end of greater diameter than the other, each of said partitions comprising a single sheet of material of generally rectangular configuration folded intermediate its length to form a base portion having two contacting layers of material; each contacting layer including a double thickness flange extending at right angles to the base portion and formed by folding a corresponding intermediate area of each base portion upon itself, the flanges in the respective contacting layers extending from the base portion in opposite directions; each flange provided with a slot extending from the middle of the outer edge thereof toward the base portion and having a width substantially equal to the thickness of another double thickness flange of a like partition whereby when the flanges of two partitions are brought into interengaging right angle relation with the slots in each aligned with one another, the top edges of the flanges form supports for spacing apart the base portions of adjacent partitions and divide the space between the base portions of adjacent partitions into four cop-receiving pockets of equal size; each contacting layer of said base portion on both sides of said flange provided with holes which are in axial alignment with one another, the holes in one layer having a diameter slightly larger than the small end of the cop and the holes in the other layer having a diameter slightly larger than the large end of the cop whereby the edges of said holes position the cops transversely on the base portions and the surface of the layer containing the smaller holes and surrounding said holes forms a support for the large end of the cops to position them against longitudinal movement.
